UNITED STATES PATENT OFFICE.

GEORGE W. LORE, OF DEXTER, ASSIGNOR OF FOUR-FIFTHS TO GEORGE S. SILL, CHARLES T. SILL, LOUIS W. BRIGGS, AND JAMES S. SPENCER, ALL OF DETROIT, MICHIGAN.

CAN-SEAMING MACHINE.

SPECIFICATION forming part of Letters Patent No. 380,212, dated March 27, 1888.

Application filed August 30, 1887. Serial No. 248,266. (No model.)

To all whom it may concern:

Be it known that I, GEORGE W. LORE, a citizen of the United States, and a resident of Dexter, in the county of Washtenaw and State 5 of Michigan, have invented certain new and useful Improvements in Machines for Crimping and Double-Seaming Can Ends; and I do hereby declare that the following is a full, clear, and exact description of the invention, which 10 will enable others skilled in the art to which it appertains to make and use the same, reference being had to the accompanying drawings, which form a part of this specification, and in which—

15 Figure 1 is a central longitudinal vertical sectional view of my new and improved machine for crimping and double-seaming the ends of sheet-metal cans, &c. Fig. 2 is a perspective view taken from the lower end of the same. 20 Fig. 3 is a longitudinal vertical central sectional view of a slightly-different form of my new and improved machine. Fig. 4 is a bottom plan view of the construction shown in Fig. 3, the rolls being shown in dotted lines. 25 Fig. 5 is a vertical sectional view taken on line $\alpha\alpha$ of Fig. 4. Fig. 6 is a vertical sectional view showing a slight modification, which will be hereinafter described; and Fig. 7 is an enlarged view in elevation of the machine, taken 30 midway between rolls of two different kinds, and showing the means for rotating the sleeve.

The same numerals of reference indicate corresponding parts in all the figures.

My invention consists in a new and improved machine for crimping and double-seaming the ends of sheet-metal cans and other similar bodies; and my invention will be hereinafter fully described and claimed.

The great advantage of my invention is that 40 it holds the sheet-metal can perfectly still, while the crimper or double-seaming rolls whirl around or revolve. The advantages of having the cans stand still are these. If the can is whirling around when the soldering-flux is put on, two-thirds of this flux will fly or be thrown off by the centrifugal action, which to this extent defeats the object of putting on the soldering-flux, besides making it more difficult to solder the caps on the cans. It also increases

greatly the expense and the amount of soldering material or "flux" required. Where "acid" or "soldering-salts" are used they fly all over the clothes of the operator, as well as over the machine itself, and in closing paint-cans and cans containing other liquids the 55 whirling can will discharge a part of its contents, making it very disagreeable for the operator, besides wasting the material.

In my new and improved machine the cans stand still; hence the soldering-flux put on 60 will stay where it is placed, and in sealing cans containing liquids none of their contents will escape and fly out, as the can is standing perfectly still, the crimping or double-seaming rolls revolving around the can. A consider- 65 able amount of time is saved in placing the cans in the machine and removing them, as owing to their standing stationary it is not necessary to wait for the can to get in motion, or to wait to seize it to remove it, as is necessary with revolving cans. In machines in which the cans are revolved, where their longitudinal side seams are soldered with acid or soldering-salts, the 70 whirling cans will cut and wear the fingers of the operator speedily when placing them in 75 position and removing them.

Referring to the several parts by their designating-numerals, 1 indicates the stationary vertical shaft of my new and improved machine, as shown in Figs. 1 and 2, this stationary shaft being secured at its upper end in a frame, 2, of ordinary or usual construction, so that it can be readily raised or lowered vertically in order to place the can beneath its lower end or to remove it when finished, 80 and thus be retained in its adjusted position by means of a set-screw, 1^a. Upon the lower end of this shaft 1 is rigidly secured the centering-chuck 3, which rests upon the top of the can and holds it stationary in position. 85 This stationary shaft 1 can be adjusted vertically by a suitable hand-lever of ordinary construction; or the drive mechanism may be arranged to raise it automatically as soon as each can is finished.

90 4 indicates a revolving sleeve, which is supported by any ordinary means, a bracket, 4^a, however, being shown in the accompanying

drawings, for convenience of illustration. This sleeve fits and revolves upon the stationary shaft 1, and carries at its lower end the head in which the adjustable levers are secured 5 which carry the crimping and double seaming rollers. This sleeve is rapidly revolved by means of any ordinary drive mechanism or belting from a source of power, a pulley and bolt, 4^a and 4^b, respectively, for convenience, 10 being shown. Upon the lower end of this revolving sleeve is rigidly secured the head 5, which in Figs. 1 and 2 of the drawings is shown of a conical shape, with its concave side downward. This head is formed with the four 15 radiating slots, 6, formed equidistant from each other, as shown, and in these radiating slots are adjustably secured the levers 7 7, which carry on their lower ends the crimping or double-seaming rolls. These rolls are 20 movably secured upon the lower ends of the adjustable levers 7 by the pivot-pins 8, and can be removed and changed, using rolls of different forms, according to the work to be performed, the shape of the can end, &c. In 25 Figs. 1 and 2 these four levers are shown pivoted centrally upon the transverse pivots 9, the ends of which are held firmly against the lower side of the head 5 by the arms 10 10 of the bifurcated outer ends of adjusting-plates 30 11, each of which is firmly held in its adjusted position against the lower side of the head 5, over that particular radial slot 6, by a screw, 12, which passes through the said slot and has a nut, 13, on its upper threaded end. It will 35 be seen that by this construction and arrangement of parts, by loosening the nuts 13, the levers can be adjusted in or out in the slots 6 to suit the size of the cans to be operated upon.

Upon the revolving sleeve 4, above the head 40 5, are mounted two collars, 14 and 15, which can be slid up or down upon the said sleeve, but which revolve with the same, being formed in their bores with the grooves 16, in which fits a rib or feather, 17, formed on the said 45 sleeve, which serves to carry the said collars around with the sleeve, while at the same time permitting of their being adjusted up or down on the sleeve. Each of the said collars is formed with an exterior annular groove, 18, in 50 which fit the ends of suitable levers, 19 20, of ordinary construction, for shifting the collars up and down on the revolving sleeve.

The projecting upper end of each of the four levers 7 has a longitudinal slot, 21, formed in 55 it, and in each of the said slots is pivoted the depending lower end, 22, of a yoke, 23, in which is clamped the outer end of an arm, 24. The inner ends of the arm 24 of two opposite levers, 7, are pivoted between jaws 25 25, 60 which are formed on the lower end of the lower adjusting-collar, 14, while the inner ends of the other two arms 24 24 of the other pair of opposite levers, 7^a 7^a, are pivoted between jaws 26 26, which are formed on the lower 65 ends of arms 27 27, which project downward from the lower end of the upper collar, 15,

passing through recesses 28 28 in the lower collar, 14, as shown more clearly in Figs. 6 and 7.

In operation a full can with its top placed in position is now inserted beneath the lower end of the stationary shaft 1, which is raised, and the said shaft being lowered, so that the centering chuck 3 rests upon the cap of the can, by means of the lever 20 the collar 14 can be in a moment slid down on the sleeve 4, so 75 as to swing the crimping-rolls 29 29 of the pair of opposite levers 7 7 into operative position, so that as the can is held stationary by the stationary rod and the sleeve revolves and carries the said levers and rollers around 80 with it, the rolls 29 29, which are formed with the narrow grooves 30 30, will roll up the double seams or flanges of the cap and can end. These rolls are then drawn back by drawing up their collar 14 by its lever, and the other 85 collar, 15, is then pushed down on the sleeve 4, so as to throw the other pair of opposite rolls, 7^a 7^a, in. These rolls are formed with a shallow wide groove, so as to flatten down the double seam, making a joint which is thoroughly water, oil, and air tight. These wide shallow grooves may be dispensed with in the rolls 7^a and the rolls left plain, as shown in Fig. 7 of the drawings.

One sliding collar 14, with its levers, collars, and pair of rolls, can be dispensed with for double-seaming by using on the remaining pair of levers, 7, rolls with a narrow annular groove, like those shown at 29 29, but with a longer body below the said grooves. When 95 only these two rollers are used, the shape of which is shown in Fig. 3 of the drawings, the rolls first operate, like the rolls 29, to roll up the double seams, when by raising the rolls 100 the flat body part 31 of these rolls will strike the rolled-up seam and flatten it down against the chuck 3 on the stationary shaft, which has been dropped for the last operation. These 105 adjustments or movements can be performed automatically by employing suitable mechanism.

In Figs. 3, 4, 5, and 6 of the drawings I have shown the head 5 made flat and formed with the four radial slots 6. Through two of these 115 slots pass the levers 7 7, which carry on their lower ends the crimping-rolls, and which are centrally pivoted on the pivot-pins 32, which are formed on the sides of slide-blocks 33, each of which blocks is formed with a longitudinal screw-threaded aperture, 34. Through these 120 apertures pass the adjusting-screws 35 35, which support these blocks, and which are swiveled at their inner ends to the hub 35^a of the head 5, and by means of which the said levers, with their rolls, can be adjusted in or 125 out to suit the size of the cans to be operated upon. In this form the rolls themselves are removable and changeable, as in all forms of the machine.

36 indicates the sliding collar upon the revolving sleeve, which corresponds to the collars shown in Figs. 1 and 2. It has arms 24,

pivoted at their inner ends in jaws formed upon its lower end. The outer end portions of these arms 24 pass through yokes 37 37, which are pivoted in the upper ends of the levers 7 5 7, and are held adjustably therein by means of the set-screws 38 38. It will be seen that the "pitch" or angle of the rolls can be adjusted by adjusting the angle of the levers 7 7 by means of these set-screws 38, and the same object is effected in the construction shown in Figs. 1 and 2 by means of the screws 39, which pass through the ends of the yokes 23 and have the nuts 40 on their threaded ends.

Instead of the levers 7 7 being centrally pivoted, as shown in Figs. 3, 4, and 5, they may be pivoted on the lower side of the head 5 on pivots 41 41, which are secured in the outer ends of adjustable plates 42, which are held adjustably in position by the bolts or screws 20 43, which pass entirely through the radial slots 6, and have their threaded lower ends screwed into threaded apertures 44 in the plates 42, as shown, their heads resting upon the upper side of the slotted head 5.

25 Through two opposite slots, 6, in the flat head 5 (shown in Figs. 3, 4, and 5) pass the screws 45 45, which hold adjustably in position the stems 46 46, to the lower ends of which are pivoted the rolls 47 47, which are set at an angle or inclination for the purpose of turning down the burr of the can ends before the other pair of rolls on the levers 7 7 are brought down and in by the collar 14 and its operating lever 20 to finish the seam.

35 From the foregoing description, taken in connection with the accompanying drawings, the construction, operation, and advantages of my invention will be readily understood. It will be seen that my new and improved machine is strong and comparatively simple in construction and exceedingly rapid and efficient in its operation. It can be run at a higher rate of speed than any other machine

of its class, even up to one thousand revolutions. It is adjustable to the different sizes of cans, and an indefinite number of different-shaped rolls can be used, giving it a greater variation than any other machine made. The can being operated upon stands still, as before clearly described, thus giving the machine the great advantages heretofore set forth over those in which the can is whirled around.

Having thus described my invention, what I claim, and desire to secure by Letters Patent of the United States, is—

1. In a machine for crimping and double-seaming can ends, the combination of the vertically-adjustable and non-rotatable rod having the centering-plate secured upon its lower end, the revolving sleeve having the radially-slotted head secured upon its lower end, the pivoted levers adjustable in said slots, a roll removably journaled upon the lower end of each of said levers, the sliding collar formed with the annular groove, the pivoted arms, and pivoted adjustable yoke, and a lever engaging the said groove for operating the collar.

2. In a machine for crimping and double-seaming can ends, the combination of the vertically-adjustable and non-rotatable rod having the centering-plate secured upon its lower end, the revolving sleeve having the radially-slotted head secured upon its lower end, the bifurcated adjustable plates, levers, each having a roll removably journaled upon its lower end, the sliding collar formed with the annular groove, the pivoted arms, and pivoted adjustable yokes, and a lever for engaging said groove for operating the collar.

In testimony that I claim the foregoing as my own I have hereunto affixed my signature in presence of two witnesses.

GEORGE W. LORE.
